UNITED STATES PATENT OFFICE.

HEMAN OSBORNE, OF NEW YORK, N. Y.

WINDOW-SASH FASTENER.

No. 904,145.

Specification of Letters Patent.

Patented Nov. 17, 1908.

Application filed March 25, 1907. Serial No. 364,924.

To all whom it may concern:

Be it known that I, HEMAN OSBORNE, a citizen of the United States of America, and resident of New York, in the county of New York and State of New York, have invented 5 certain new and useful Improvements in Window-Sash Fasteners, of which the following is a full, clear, and exact description.

The object of this invention is to provide a 10 fastening device for sashes which will be simple and inexpensive of construction, practicable of application for its locking operation on the window casing, susceptible of being operated to lock or release the sash or 15 sashes only within the room,—and positive and certain in its window locking action.

The invention consists in the combination 20 and arrangement of parts and the construction of certain of the parts all substantially as hereinafter fully described and set forth in the claims.

The improved window fastening is illustrated 25 in the accompanying drawings in which,—

Figure 1 is a horizontal sectional view through a window casing at about the level of the meeting rail of the upper and lower sashes and through portions of the window fastening device which is shown as fitted into 30 the window casing. Fig. 2 is an elevation and partial vertical section as seen from the inner or concealed side of the window casing stile, or as looking beyond the plane indicated by line 2—2, Fig. 1. Line 1—1, on 35 Fig. 2 indicates where the parts in section in Fig. 1 are taken. Fig. 3 is a perspective view of a portion of the window casing in which the locking devices for both sashes are fitted,—the sashes not being shown. Fig. 4 is 40 a view of a corner portion of a sash showing a series of bolt engagement sockets therein.

Similar characters of reference indicate 45 corresponding parts in all of the views.

In the drawings,—A represents the window 50 casing of which B is the stile, C the stop or vertical casing strip on the inner or room side, and a a are the grooves or slide ways for the inner and outer sashes D and E, said grooves being separated by the parting bead b.

F represents the supporting plate comprised in and constituting the frame of the locking device fitted within the window casing and sunk within the walls of the vertical 55 sash guide ways or grooves a a. Said plate comprises a horizontal member 10 and up-

wardly and downwardly extending members 12 and 13 projecting from different portions of the length of the horizontal member 12 in parallelism and along the line of the sash grooves a a,—the window casing behind the removable parting bead being mortised and adapted for the reception of said supporting plate, and suitably open, as shown in Fig. 1 at a, behind such plate for the accommodation of the movable parts of the present device which are mounted on the inner or rear side of the support plate.

13^a represents the four screws for fastening the plate comprising the double arms 12 70 and 13 thereof.

G and H represent a pair of levers intermediately fulcrumed for swinging movement in parallel horizontal planes at the rear side of the horizontal member 10 of the 75 support plate, these levers being fulcrumed at 15 and 16 to ear pieces 17 formed as integral parts of the support plate. The arms of the 80 said levers G and H which are extended towards the room side of the window casing 85 have push-rods G² and H² pivotally or otherwise suitably connected therewith, said rods projecting through openings 19, 19 formed in said plate and also through the window casing strip or stop C; and, as shown, these 90 holes 19 and the headed or button provided push rods which project therethrough advantageously have their locations closely together and one directly above the other, at points inwardly offset from the sash groove. 95

G³ and H³ represent another pair of levers fulcrumed respectively to ear pieces 20 and 21 at the rear sides of the downwardly and upwardly extended members 13 and 12 of the 100 said support plate,—these intermediately pivoted levers G³ and H³ being arranged at right angles to the aforesigned levers G and H and the lever G³ has the end of one arm thereof jointed to the proximate end of the lever G while the lever H³ has the end of one 105 of its arms jointed to the end of the lever H which meets it at right angles.

G⁴ and H⁴ represent axially horizontal locking bolts with which the oppositely extended ends of the levers G³ and H³ have connections or engagements, these being guided and normally projecting outwardly through the aforesaid downwardly and outwardly extending support plate members 13 and 12, and beyond the walls of the sash guiding grooves 110 at different heights; and these bolts are adapted to engage in any one of the several

sockets j in the edges of the inner and outer sockets.

g and h represent springs, each reacting against a lever of each of a set of compound 5 levers pertaining to a given locking bolt and operative to maintain the bolts normally in their sash locking positions and the push rods and the intervening compound lever connections correspondingly positioned.

10 As constructed by me, each vertical support plate member, right angularly extended from the horizontal portion 10, is made with a tubular integrally formed bolt guide m having a slot m^2 through its side, for the entrance therethrough of the tongue like end of the adjacent bolt operating lever G^3 or H^3 , such tongue like lever end entering a slot or bifurcation in the inner end of the locking bolt and being jointed thereto by a pivot, as 15 shown at o in Fig. 2.

The supporting plate having the several lever supporting ear lugs and the tubular bolt guides may be produced as a metal stamping or as a light casting; and the sockets j in the 20 vertical edges of the sash are preferably to be provided with tubular metallic bushing j^2 .

In operation, as manifest, an inward movement imparted to the upper push rod H^2 will 30 impart through the compound lever connections a corresponding inward and sash unlocking movement to the locking bolt H^4 for the upper sash, leaving such sash free to be opened as far or as slightly as may be desired, to be again locked by engagement of the locking bolt in whatever socket in the sash edge may become alined therewith; and the inward forcing of the lower push rod effects a like operation of the locking bolt for 35 the other sash.

I claim:—

1. In a window fastener, a support, adapted to be set in a window casing within and adjacent the sash way or groove thereof, 45 having a lever fulcrumed thereon, a push-rod connected to a member of said lever and adapted to project through an opening

therefor in the casing to one side of the sash groove, another lever fulcrumed on said support and engaged with the first lever, a locking bolt with which the second lever is connected and normally projecting outwardly beyond the wall of the sash guiding groove, and adapted to engage in a socket therefor in the edge of a sash, and a spring 55 for maintaining the parts with the bolt normally in its projected locking position.

2. In a window fastener a support plate, adapted to be transversely set in a window casing within and adjacent the sash grooves 60 thereof, comprising a horizontal member, and upwardly and downwardly extended members projecting from different portions of the length of such horizontal member, a pair of levers intermediately fulcrumed for 65 swinging movements in parallel planes on the rear side of said horizontal member, a pair of push-rods connected to a member of each of said levers, and adapted to project through openings therefor in the casing inwardly beyond the sash grooves, another 70 pair of levers fulcrumed respectively at the rear sides of the said upwardly and downwardly extended members of said support plate, and arranged at right angles to, and each connected with, one of said first named levers, axially horizontal locking bolts with which the oppositely extended ends of said second levers are connected, and normally projecting outwardly beyond the walls of 75 the sash guiding grooves at different heights in the length of said grooves and adapted to engage in sockets therefor in the edges of both sashes for a window, and springs for maintaining the parts with the bolts normally in their projected, sash-locking, positions.

Signed by me at Springfield, Mass., in presence of two subscribing witnesses.

HEMAN OSBORNE.
